[57] CLAIM

The ornamental design for an automobile wheel with lights, as shown and described.

DESCRIPTION

FIG. 1 is a front perspective view of an automobile wheel with lights showing my new design;

FIG. 2 is a front elevational view thereof on a reduced scale;

FIG. 3 is a rear elevational view thereof on a reduced scale; and,

FIG. 4 is a typical side elevational view thereof on a reduced scale, all side elevational views being identical to the view shown in FIG. 4.

FIG. 1

FIG. 2

FIG. 3

FIG. 4
